ABSTRACT: The unit includes an extended foil capacitance section made up of at least a pair of electrodes convolutely wound in a capacitance relation with dielectric spacing material therebetween. A lead extends through the section in connection to one electrode, and the other electrode volutely extends beyond the one electrode to provide an electrostatic shield for the unit.

PATENTED JUL 27 1971

FILTER UNIT HAVING A CIRCUMFERENTIAL ELECTROSTATIC SHIELD

BACKGROUND OF THE INVENTION

This invention relates to filter units and more particularly to an economical filter unit which utilizes a metal film as an external shield.

In the prior art, wave filters are generally constructed with an external metal housing connected to the ground side of the capacitive element for shielding of the enclosed components from external fields. This provides a comparatively costly structure which limits its applications.

One object of this invention is to provide an economical filter unit.

Another object of this invention is to provide a filter unit having an economical outer shield.

A further object of the invention is to provide a filter unit having the ground electrode convolutely extended beyond the other electrodes so as to provide an electrostatic shield.

A still further object of this invention is to provide a filter unit having a metallized film casing.

SUMMARY OF THE INVENTION

A filter unit constructed in accordance with the invention comprises a capacitive section having at least a pair of electrodes convolutely wound in capacitive relation with dielectric spacing material therebetween, each electrode is extended from a respective end of the section, a lead extends through the center of the section and is in connection to one electrode, and the other electrode is volutely extended beyond the end of said one electrode so as to thereby provide a shield for said filter unit.

BRIEF DESCRIPTION OF THE DRAWINGS

FIG. 1 is a view in section of a filter unit provided in accordance with the invention;

FIG. 2 is a sectional view of the capacitance section of FIG. 1 taken along a plane perpendicular to its convolute winding;

FIG. 3 is a view in section of another embodiment of the filter unit;

FIG. 4 is a view in section of an embodiment of the invention which provides a T-type filter unit; and

FIG. 5 is a view in section of a π -type filter unit provided in accordance with the invention.

DESCRIPTION OF THE PREFERRED EMBODIMENT

FIG. 1 shows a filter unit 10 having an extended-foil capacitance section 12 affixed at one end to a bulkhead terminal member 14. Section 12 is shown in FIGS. 1 and 2 as being a convolutely wound section having electrodes 16 and 18 wound in extended foil fashion with interposed dielectric spacer material 20 and 22.

Section 12 is affixed to terminal 14 by connection of electrode 18 to the terminal by solder 24 or the like. A feed-through lead 26 is connected to electrode 16, by solder 28 or the like at the other end of section 12. Lead 26 passes through mandrel hole or bore 30 of section 12 and is insulated from terminal 14 by a dielectric plastic material 32 such as an epoxy resin or the like which is molded within mounting stud 34 of terminal 14.

Shielding of filter unit 10 is provided in this embodiment by convolutely extending the ground electrode or terminal connected electrode, that is, electrode 18 in this case, beyond the electrode 16 as depicted in FIG. 2. As shown in this figure, electrode 18 is convolutely extended to and preferably beyond the end 36 of electrode 16 such that electrode 18 provides a circumferential shield encompassing section 12. Advantageously, dielectric 22 is also convolutely extended with electrode 18 to provide an insulative covering around the unit.

The unit is constructed by first winding a section 12 in a conventional manner, with however, one foil convolutely ex-

tended outside of the other and preferably beyond the end thereof. The outside foil is then connected to the terminal or ground side of the filter unit while the other, inner, electrode is connected to a feed-through lead as shown.

Of course, many different materials may be employed in this construction. For example, section 12 may be constructed from metal foil such as zinc or aluminum or the like and dielectric spacer strips of kraft paper or suitable plastic or the like.

Metallized film-type sections may also be employed. Advantageously, if the section is rolled with its metallic deposit on the inner surface of the plastic film, an outer insulative covering having an inner conductive shield is inherently provided.

The shielding casing can also be provided by a metallized tape or sleeve 40, as shown in FIG. 3, which is in connection to ground electrode 18 and provides a shieldlike extension of it. Sleeve 40 is made up of a dielectric film 42 such as polyethylene or the like which is coated on its inner surface with conductive material 44 of aluminum or the like.

Casing 40 is constructed so as to allow contact of its inner conductive deposit 44 to ground electrode 18 of the filter. This is accomplished in the illustrated embodiment by contact

of film 44 to an outer portion of header 14. Conductive film 44 is extended throughout the full length of the section but spaced from the positive or line side of the filter unit; that is, the metallizing 44 is terminated at the corner 46 and is spaced from the positive electrode 16 and its interconnecting solder 28. This provides an effective Faraday shield on the unit 10 which terminates or grounds external electrostatic fields. Consequently, any stray fields must feed into the line on its positive side.

FIG. 4 illustrates a T-type filter which is constructed in a manner similar to that described above, with however, the addition of inductors 50 and 52 spaced at either end of the section 12. Inductive element 50 and 52 are connected in series with lead 26. Inductor 50 is disposed, in this case, within the plastic seal 32 of bulked mounting terminal 14 while inductor 52 is disposed in additional plastic material 54 which covers the line end of the section 12.

An insulative washer 56 is disposed between element 50 and the adjacent end of section 12 and a pair of similar washers 58 and 60 are provided at the other end of the section to insure insulation of inductor 52. It should be noted that washer 60, which is mounted at the extreme end of the unit provides support for the film 42 which in this case is extended around inductor 52 at the positive end of the unit.

As in the previously described embodiments, the shielding deposit 44 is stopped just prior to the positive end of section 12, so as to prevent any possibility of contacting the positive electrode or inductor 52. The conductive shield 44 may, of course, be extended alongside inductor 52 if steps are taken to provide adequate insulation between the shield and the line elements.

Advantageously, an L-type unit can be provided by eliminating one or the other inductor elements. Preferably, inductor 50 is retained since this provides a more compact unit in which the inductor is conveniently disposed within the header 14. It should be understood, of course, that in structures where room for the inductive element 50 is not permitted within the header it may be advantageous to provide the L-type unit with an inductive element disposed at the positive end of the filter.

The mandrel hole 30 may also be utilized to store the inductor, for example, ferrite beads or a ferrite slug inductor may be mounted on lead 26 and disposed within mandrel hole 30 of section 12 to provide L- and T-type filter units.

A π -type filter may also be constructed in accordance with the invention as shown in FIG. 5 wherein a pair of concentric capacitance sections 64, 66 are interconnected with an inductive element 68. Inductor 68, which may be a coil or the like is mounted at the positive end of the filter structure in series connection between the positive foils of section 64 and 66.

Hence, coil 68 is connected at one end to lead 26, which is connected by solder 70 to the positive electrode (not shown) of the inner capacitance section 64, while the other end of inductor 68 is connected to the positive electrode (not shown) of capacitance section 66 by a ring 72 of solder or the like, which is concentric to solder 70. A line terminal 74 is also provided in connection to the positive foil of capacitor 66 by solder 72. The negative or ground electrode of each section is connected to terminal 14 by solder as shown at 76, and the unit is completed by enclosing section 66 and coil 68 within metallized film 40.

In this construction metallic deposit 44 is longitudinally extended beyond the end of section 66 and alongside inductor 68 so as to also provide an electrostatic shield for this element. It should be understood, of course, that shield 44 may also be brought around the end of the unit as long as it is adequately insulated from both the inductive element and the positive electrodes.

Many different embodiments are possible, of course. For example, the inductive elements may be inductive coils having molybdenum cores or the like; or may be other inductive components. In addition, more complicated filters may be constructed in the above manner for example, by splitting its capacitive windings into more portions and utilizing additional inductive elements.

In the π -type unit of FIG. 5, as well as in any of the other embodiments, the outer shield may be conveniently provided by convolutely extending the ground electrode of the outermost section (section 66 in this case) beyond its negative electrode.

The metallized film may be employed in any embodiment as a shield if desired, and contact to the ground side of the unit may be by means of the ground terminal or by direct contact to the ground electrode at the circumference of the capacitance section.

Where a metallized sleeve or the like is utilized, the ground electrode need not convolutely extend beyond the negative electrode since the sleeve serves as the electrostatic shield, however, the negative electrode must in any case be circumferentially insulated, as for example by convolutely extending one of the dielectric spacers of the section outside of this electrode and at least to its end.

As indicated, sleeve 40 may be a tape wound around and affixed to the unit, for example by an adhesive between its overlapping portions, or may be a heat shrinkable tubing which is thermally shrunk around section 12 and header 14.

Thus many different embodiments are possible without departing from the spirit and scope of the invention, and it should be understood that the invention is not to be limited except as in the appended claims.

What I claim is:

1. A filter unit comprising a capacitive section having at

least a pair of electrodes separated by dielectric material and convolutely wound in capacitive relation, one of said electrodes extended from one end of said section and interconnected therewith, the other of said electrodes extended from the other end of said section and interconnected therewith; a lead extended through the center of said section, said lead in connection to said one electrode at said one end and insulated from said other electrode, and said other electrode volutely extended by a metallized film circumferentially shrunk around said section with its metallic deposit in connection to said other electrode at said other end for providing a circumferential electrostatic shield of said unit.

2. The filter unit of claim 1 including an inductive element disposed at one end of said section in connection to said one electrode.

3. The filter unit of claim 1 wherein said metallized film is a sleeve of shrinkable material, said sleeve having said metallic deposit on the inner surface thereof, and said sleeve shrunk fit around said section to provide said connection between said deposit and said other electrode.

4. The filter unit of claim 1 including an inductive element serially connected to said lead at an end of said section, and said metallized film extends around at least the perimeter of said element.

5. The filter unit of claim 1 wherein said film is heat shrinkable tubing which is thermally treated in situ to shrink tightly around said section.

6. The filter unit of claim 1 including a conductive terminal conductively affixed to said other electrode at said other end, said terminal having a substantially centrally located aperture therein, said lead extending through said aperture and spaced from the walls thereof, and said film encircles the perimeter of said terminal with said metallic deposit thereof in contact with said perimeter.

7. The filter unit of claim 6 including a second capacitance section convolutely wound concentric with the first section, said second section having one electrode extended at said one end and its other electrode extended at said other end and in connection to said terminal therewith, an inductive element disposed on said one end in serial connection between said lead and said one electrode of said second section, and a terminal lead extending from said one electrode of said other section so as to provide a π -type filter.

8. The filter unit of claim 6 including an inductive element disposed within said aperture, and said element serially connected to said lead within said aperture to provide an L-type filter.

9. The filter unit of claim 8 including another inductive element disposed on said one end of said section and said other element in serial connection to said lead to provide a T-type filter.
